UNITED STATES PATENT OFFICE.

HENRY L. PITMAN, OF EAST ORANGE, NEW JERSEY, ASSIGNOR TO UNDERWOOD COMPUTING MACHINE COMPANY, OF NEW YORK, N. Y., A CORPORATION OF NEW YORK.

TYPE-WRITING MACHINE.

1,248,420.

Specification of Letters Patent. Patented Nov. 27, 1917.

Application filed February 25, 1916. Serial No. 80,419.

To all whom it may concern:

Be it known that I, HENRY L. PITMAN, a citizen of the United States, residing in East Orange, in the county of Essex and State of New Jersey, have invented certain new and useful Improvements in Type-Writing Machines, of which the following is a specification.

This invention relates to typewriting machines, and more particularly to improved means for adjusting the keys of the machine to the proper heights, and is of particular advantage where the parts have to be made comparatively rigid and heavy, as in a combined adding and typewriting machine.

In machines of this character it has been found that when assembling the machine or when making repairs, such as the internal changing of parts of the printing mechanism, that the keys of the machine will not always rest in proper position, some standing above others. This may be due to the fact that the parts are not properly fitted, or to some other irregularities such as the type cushion being of various thicknesses. This condition, however, is objectionable, as the machine would not look well and would not be easy to operate speedily; and it may also cause faulty operation of parts of the machine with which the keys coöperate, for instance, the mechanism which is to lock the keys at the end of the line (by means of a bail which rocks under hooks on the key levers) for, if the hooks are not in proper position, they may prevent the bail from rocking under the hooks of the other keys.

A feature of this invention is the provision of novel and inexpensive means for adjusting the parts, so that the keys have a uniform height, without weakening any of the parts, and also without regard to the pliability of the metal. This may be done by mounting one of the connections between the types and the keys, on an adjustable arm, the latter being mounted on the key lever.

Another feature is the convenient arrangement of the parts to be readily accessible and adjusted in a short time. This may be done by so positioning the adjusting members that they will be readily ac-

cessible from the outside of the machine without dismantling its parts. The adjusting elements may consist of screws having slotted heads facing outwardly, in which case no special tools need be employed for making adjustment.

Other features and advantages will hereinafter appear.

In the accompanying drawings,

Figure 1 is a side elevation showing the relative position of the parts of an Underwood typewriter, including my invention applied thereto.

Fig. 2 is a perspective view of the type action of said machine, with my invention applied thereto, the parts being in normal position, with the type bar resting on the cushion of said machine.

Fig. 3 is a plan view of the adjustable member of my invention, with a part broken away to show the shouldered rivet, the other parts being shown in dot-and-dash lines.

Fig. 4 is a side elevation of the same.

In the form of the invention herein disclosed, it is indicated as being applied to an Underwood typewriter, comprising keys 6, mounted on key levers which are pivotally mounted on rod 7, each key lever being provided with a stud 8, engaging a forked arm 9, of an interponent 10, fulcrumed on a rod 11, and having an upwardly extending arm 12, provided with a stud 13, engaging a cam slot 14, in a type bar 15. When a key is depressed the stud 8 rides in the forked arm 9, thereby camming the interponent 10 forwardly so that the stud 13 in the arm 12 of the interponent 10 rides in the slot 14 of the type bar 15, and swings the type bar upwardly and rearwardly about a fulcrum rod 16, against the platen 17. After the key has been released, a spring 18, resting on a bar 19 on the frame of the machine, and bearing on the key lever, returns the parts to normal positions, the type bar 15 striking a cushion 20.

When assembling the machine, or when making repairs, such as placing new type bars in the machine, it has been found that the rows of keys do not always lie level or even. This condition arises because of irregularity in the parts which form the connections between the key levers and the type bars. For instance, the cam-slot 14

of the type bar may be either too long or too short, or the cushion 20 may be of uneven thickness, in which case the type bars and the keys would not rest in proper positions, presenting an unsightly appearance and being awkward to operate. Moreover a key lever may not rise high enough to permit the usual locking bail 21 to swing under the hooks 21^a of the keys.

10 Heretofore the manufacturer or repairer would either remove the parts and fit them properly, consuming much time, or "maul" the keys near the rod 7 with a special tool, thereby raising or lowering the key levers 15 at the keyboard to proper position. This weakens the key levers, rendering them liable to breakage.

To obviate the above difficulties in a convenient and inexpensive manner, without 20 weakening any of the parts, I mount the stud 8 of the key lever upon an arm 22. This arm may be pivotally secured to the key lever by a rivet 23, having a shoulder 24 which acts as a spacer between the key 25 lever and the arm 22. The arm 22 may be bent out from the key lever at 25, to clear the forked arm 9, so that the stud 8 may extend through said forked arm between the key lever and the arm 22. Therefore 30 the device may be placed on the machine without changing the usual position of the parts relatively to the interponent 10.

The arm 22 is variable as to height, being provided with a portion 26 bent around under the key lever at a considerable distance therefrom. Two screws 27 and 28 are placed at opposite sides of the rivet 23 which forms the pivot for the arm 22, and bear upwardly against the key lever to hold 40 the arm 22 stationary with the key lever.

To adjust the arm to various heights, and thereby permit the spring 18 to restore the key accordingly, it is simply necessary to loosen and tighten the screws 27 and 28. 45 For instance, if it is desired to raise the key at the keyboard, the screw 28 is withdrawn and the screw 27 tightened, thereby rocking the arm 22 to relatively lower the stud 8 and thereby allow the key to rise. 50 If it is desired to lower the normal position of a key, the screw 27 is withdrawn and the screw 28 tightened, thereby raising the stud 8 and forcing the key down.

The screws 27 and 28, being upon opposite sides of the pivot of the arm 22, tighten 55 against one another, thereby locking the device against accidental displacement; and are provided with slotted heads, so as to be easily manipulated by an ordinary screwdriver.

It will be seen that in placing the screws on the bottom of the key levers, they are very accessible, since in order to make adjustment it is simply necessary to turn the 60 machine over.

In combined typewriting and computing machines in which the keys actually do the computing, such as shown in my co-pending application, No. 24,390, filed April 28, 1915, in which the key levers are provided with 70 cams 30 rocking a bail 31 for turning the number into the computing wheels, the amount of rotation given to the computing wheels depends upon the throw of the cams on the key levers; therefore the throw of 75 the key must be very exact. In order to get this exact throw, the key levers for the numeral keys must be very rigid, and are therefore made of heavy material. It has been found that these key levers are too 80 heavy to "maul" and therefore this invention is of particular advantage when used on the numeral key levers of a combined typewriting and computing machine. As in the said application, the universal bar 32 85 operated by a nib 33 of the type bar, controls the escapement of the typewriter, and also operates part of the computing mechanism.

Variations may be resorted to within the 90 scope of the invention, and portions of the improvements may be used without others.

Having thus described my invention, I claim:

1. In a typewriting machine, the combination with a type-bar and a key, of means for transmitting motion from the key to the type-bar, said motion-transmitting means including two entrained elements having an adjustable connection therebetween, said connection comprising a pivoted arm and two opposing screws for adjustably fixing the relative angular position of the arm with respect to the element by which it is carried.

2. In a typewriting machine, the combination with a type-bar and a key, of means for transmitting motion from the key to the type-bar, said motion-transmitting means including two entrained elements having an adjustable connection therebetween, said connection comprising a pivoted rocker and two screws for adjustably fixing the relative angular position of the rocker, said screws being oppositely located with respect to the center of motion of said rocker so that each screw tends to oppose the effect of the other.

3. In a typewriting machine, the combination with a type-bar, a key lever, and an interponent for transmitting motion from said key lever to said type-bar, of an adjustable connection between said key lever and said interponent comprising an arm pivotally movable with respect to said key lever and having a motion-transmitting engagement with said interponent, and two screws for adjustably fixing the relative angular position of said arm with respect to said key lever, each screw being threaded in

- one of said pivotally related members and having a part to be forced against the other on rotation of said screw in one direction, the action of each screw when so rotated, 5 tending to oppose the action of the other.
4. In a typewriting machine, the combination with a type-bar, a key lever, and an interponent for transmitting motion from said key lever to said type-bar, of an adjustable connection between said key lever and said interponent comprising a rocker pivotally movable with respect to said key lever and having a motion-transmitting engagement with said interponent, and two screws for adjustably fixing the relative angular position of said rocker with respect to said key lever, each screw being threaded in one of said pivotally related members and having a part to be forced against the other 10 on rotation of said screw in one direction, said screws being oppositely located with respect to the relative center of motion between said rocker and said key lever, so that each screw tends to oppose the effect of the other 15 when so rotated.
5. In a typewriting machine, the combination with a type-bar, a key lever, and an interponent for transmitting motion from said key lever to said type-bar, of an adjustable connection between said key lever and said interponent comprising a rocker pivotally movable with respect to said key lever and having a motion-transmitting engagement with said interponent, and two screws for adjustably fixing the relative angular position of said rocker with respect to said key lever, each screw being threaded in the rocker and having a part to be forced against the key lever, said screws being oppositely located with respect to the relative center of motion between said rocker and said key lever, so that each screw tends to oppose the effect of the other when so rotated. 20
6. In a typewriting machine, the combination with a type-bar and a key, of means for transmitting motion from the key to the type-bar, said motion-transmitting means including two elements having an adjustable connection therebetween, said connection comprising an arm pivotally movable with respect to one of said elements and having a movable engagement with the other, and two screws, accessible for operation from the outside of the machine, for adjustably fixing the relative angular position of the arm with respect to said pivotally related element, each screw being threaded in one of said pivotally associated members and having a part to be forced against the other on rotation of said screw in one direction, the action of each screw when so rotated tending to oppose the action of the other. 25
7. In a typewriting machine, the combination with a type-bar and a key, of means for transmitting motion from the key to the type-bar, said motion-transmitting means including two elements having an adjustable connection therebetween, said connection comprising a rocker pivotally movable with respect to one of said elements and having a movable engagement with the other, and two screws, accessible for operation from the outside of the machine, for adjustably fixing the relative angular position of the rocker with respect to said pivotally related element, each screw being threaded in one of said pivotally associated members and having a part to be forced against the other on rotation of said screw in one direction, said screws being oppositely located with respect to the relative center of motion between said member and rocker so that each screw tends to oppose the effect of the other when so rotated. 30
8. In a typewriting machine, the combination with a type-bar and a key, of means for transmitting motion from the key to the type-bar, said motion-transmitting means including two elements having an adjustable connection therebetween, said connection comprising a rocker pivotally movable with respect to one of said elements and having a movable engagement with the other, and two screws, accessible for operation from the outside of the machine, for adjustably fixing the relative angular position of the rocker with respect to said pivotally related element, each screw being threaded in the rocker and having a part to be forced against said pivotally related element, said screw being oppositely located with respect to the relative center of motion between said last-mentioned element and rocker so that each screw tends to oppose the effect of the other when so rotated. 35
9. In a typewriting machine, the combination with a type-bar, a key lever, and an interponent for transmitting motion from said key lever to said type-bar, of an adjustable connection between said key lever and said interponent comprising an arm pivotally movable with respect to said key lever and having a motion-transmitting engagement with said interponent, and means, accessible for operation from the outside of the machine, for adjustably determining and fixing the relative angular position of said arm with respect to said key lever. 40
10. In a typewriting machine, the combination with a type-bar, a key lever, and an interponent for transmitting motion from said key lever to said type-bar, of an adjustable connection between said key lever and said interponent comprising an arm pivotally movable with respect to said key lever and having a motion-transmitting engagement with said interponent, and two screws providing means, accessible for operation from the outside of the machine, for 45

adjustably fixing the relative angular position of said arm with respect to said key lever, each screw being threaded in one of said pivotally related members and having a part to be forced against the other on rotation of said screw in one direction, the action of each screw, when so rotated, tending to oppose the action of the other.

11. In a typewriting machine, the combination with a type-bar, a key lever, and an interponent for transmitting motion from said key lever to said type-bar, of an adjustable connection between said key lever and said interponent comprising a rocker pivotally movable with respect to said key lever and having a motion-transmitting engagement with said interponent, and two screws providing means, accessible for operation from the outside of the machine, for adjustably fixing the relative angular position of said rocker with respect to said key lever, each screw being threaded in one of said pivotally related members and having a part to be forced against the other on rotation of said screw in one direction, said screws being oppositely located with respect to the relative center of motion between said rocker and said key lever, so that each

screw tends to oppose the effect of the other when so rotated.

12. In a typewriting machine, the combination with a type-bar, a key lever, and an interponent for transmitting motion from said key lever to said type-bar, of an adjustable connection between said key lever and said interponent comprising a rocker pivotally movable with respect to said key lever and having a motion-transmitting engagement with said interponent, and two screws providing means, accessible for operation from the outside of the machine, for adjustably fixing the relative angular position of said rocker with respect to said key lever, each screw being threaded in the rocker and having a part to be forced against the key lever, said screws being oppositely located with respect to the relative center of motion between said rocker and said key lever, so that each screw tends to oppose the effect of the other when so rotated.
